UNITED STATES PATENT OFFICE.

FRIEDRICH DÖPPENSCHMITT, OF PFORZHEIM, GERMANY.

BEADED ARTICLE OF JEWELRY.

Application filed December 4, 1923, Serial No. 678,481, and in Germany January 22, 1923.

This invention relates to beaded articles of jewelry, such as bracelets and the like, and particularly to an article of jewelry in which the beads forming the surface component of the article are mounted upon a form defining and maintaining flexible or more or less resilient core.

Beaded articles of jewelry are much in vogue and are sold in large quantities in various sections of the globe. Their popularity is due to the fact that articles of from good to very fine appearance may be made to sell at moderate prices, and are capable, owing to the many changes of design or pattern possible by the use of different kinds of beads of various metals or other materials, or combinations of them, of being produced in many attractive styles to suit the caprice or fancy of the users within popular price limits. Because, also, such jewelry may be quickly modified to conform to changing style demands, without additional overhead costs or the use of different machinery, the manufacturer is enabled to put out many different styles and to constantly make and sell his goods at a comparatively low cost for any given grade of article notwithstanding frequent style changes, with resultant advantage to the retail trade and users of this class of jewelry.

Beaded jewelry as heretofore manufactured, however, has been subject to certain inherent defects. If the article, for example, is composed of beads strung upon a core composed of an elastic cord or tape, stretching of the tape, which very quickly occurs, causes deformation of the article and gapping of the beads, producing exposure of the unsightly cord or tape. The rubber content of the cord or tape also quickly rots, especially under certain climatic conditions, destroying the integrity of the article. In order to overcome this objection link chain cores or flat spring cores have been used, but chain cores are not form sustaining and therefore can not be used in the construction of some articles of jewelry, and spring cores are subject to breakage from flexing actions, with the result, as in the case of elastic cores, of the possible loss of beads in addition to the destruction of an important element rendering the article unserviceable. In the case of slender chain cores stretching and breakage are also liable to occur with the objections stated. Spring cores for economical reasons are necessarily made of spring steel and in Southern climates are affected by atmos-

pheric moisture and rust, thus both increasing their liability to breakage and the unsightliness of the article in the event of gapping of the beads and exposure of the rusted core.

One object of my invention is to provide a construction of beaded article of jewelry which overcomes all of these objections to prior constructions, and which, in addition to furnishing an article of greatly increased strength and durability, also ensures against any unsightly appearance of any part detracting from the appearance of the article in the event of gapping of the beads; and a further object of my invention is to provide a beaded article of jewelry employing a steel spring core in conjunction with a tubular combined sheath for the core and support for the beads, whereby the loss of beads or other parts in the event of breakage of the core is prevented and whereby the core is protected from rust and its liability of breakage is reduced so that its period of usefulness is materially prolonged.

In the accompanying drawing illustrating my invention,—

Figure 1 is a fragmentary side elevation of an article of jewelry embodying the invention.

Figure 2 is a plan view of the same.

Figures 3 and 4 are respectively a side elevation and an end elevation of one of the beads.

Figures 5 and 6 are a side elevation and a plan view showing a modified form of the invention.

Figures 7 and 8 are side and end elevations, respectively, of one of the beads shown in Figures 5 and 6.

Referring now more particularly to Figures 1 to 4, inclusive, of the drawing, 1 designates the beads of the bracelet or other article, which are mounted upon a tubular member 2 receiving and enclosing a core 3. The core 3 is composed of a transversely flat strip or band of spring steel, of watch spring type. The tubular member 3 is of a cross-section conforming to that of the band and is adapted to more or less snugly embrace the same from end to end thereof. The beads 1 are provided with suitably shaped slots or openings through which the core 3 and member 2 pass, and whereby the beads are strung directly upon the member 2. The beads in practice may be made of gold, silver, or other metals or materials, which may be enameled

or suitably colored or ornamented in any desired way to provide an article of the desired design and degree of ornamentality. The member 2 is composed of Milanese wire fabric, of quite close mesh. This fabric is commonly formed of wire spirals intermeshed or twisted into one another so as to provide a sheet of material, which, in the construction of the member 2, is cut to size and its longitudinal edges brought into abutment and soldered or otherwise joined to produce a flattened tube. Either solid gold or silver wire may be used, or other wire plated with these metals, silver wire being that most commonly employed.

The core 3 is suitably bent or shaped to give the desired form to the bracelet or other article, which it maintains by its resiliency, while permitting the article to be applied to the wrist or neck of the wearer and to conform to the contour thereof. The mesh wire tube 2 is universally flexible and of form sustaining character and forms a stable support for the beads 1 and a sheath or covering for the core 3. Owing to its degree of flexibility and self-sustaining character, the tube 3 allows the beads and core to have an ample degree of flexion, but at the same time prevents undue flexion of the core 3 and also any sharp bending movements thereof. Thus the core is reinforced by the tube 2 to reduce its liability of breakage, to which it is subject in articles of this character, whereby its life period or period of usefulness is prolonged. If, however, breakage of the spring core should occur, the member 2 will hold the separated portions thereof confined and in proper relative position and prevent their loss, so that notwithstanding its breakage, the spring will still serve to perform its intended function.

The member 2 is of sufficiently close mesh to prevent the entrance of perspiration to the core and to largely protect the core from the effects of atmospheric moisture. Rusting of the spring core from the action of moisture will thus be prevented or deterred, a feature of importance in the use of articles of jewelry of this character in hot and moist climates. As the outer surface of the member 2 is normally largely covered and concealed by the beads, it is not necessary to subject its surface to expensive finishing operations such as would be required if such member formed the surface member of the article. When formed of gold or silver wire or wire plated with these metals, however, the surface finish of the member 2 will be sufficiently fine to give it a good appearance at points between the beads where it is exposed. The surface of the member 2 will, therefore, provide a supplemental surface of complementary character to the surface finish of the beads, whatever it

may be, so that in the event of any gapping of the beads, due to unavoidable stretching of the core and member 2, the portions of the member 2 exposed through the gaps will give a finished appearance, i. e., will not detract from the appearance of the article. Because of the fact that the beads are firmly supported by a self-sustaining wire mesh tube, which sheathes and protects the spring core from moisture and liability of breakage but which, in the event of breakage of the core, will hold the parts thereof retained and in proper relation, a construction of article is provided which is very strong and of greater lasting qualities than beaded articles of jewelry of the constructions heretofore employed. As the member 2 is practically proof against breakage even under rough usage loss of beads from breakage of its support can not under any ordinary conditions occur, since the spring core may be fractured without loss of parts affecting the integrity of the support for the beads and, in fact, without loss of any of the parts of the article. It will thus be seen that by the use of a tubular mesh wire support for the beads and sheath for the spring core an article of superior strength and wearing qualities is produced.

In Figures 5 to 8, inclusive, a modified construction is disclosed in which the spring metal core 3 is dispensed with and beads 4 are strung upon a Milanese fabric band 5 which may be of either solid structure, i. e., composed of a flat strip, or of tubular structure. In this case the member 5 provides a flexible support for the beads which is form-sustaining and to a certain extent resilient. The member 2 in this instance will provide a flexible support for the beads which is strong and durable and, in the event of its stretching, and causing the beads to gap, will, at points exposed, present a surface of sufficiently fine appearance, complementary to that of the beads, to maintain and prevent any detract from the ornamental appearance of the article.

Having thus described my invention, I claim:

A form-sustaining resilient beaded article of jewelry comprising a spring steel core, a tubular covering of flexible, close-mesh wire fabric enveloping the core, and a string of beads surrounding the covering from end to end thereof in abutting contact with each other, said covering presenting a supplemental display surface of complementary character with respect to the display surfaces of the beads for maintaining a generally uniform appearance of the article in the event of the gapping of the beads and the exposure of the covering therethrough.

In testimony whereof I affix my signature.
FRIEDRICH DÖPPENSCHMITT.
